COMBINED KEYRING AND FLASHLIGHT

Sidney Schwartz, New York, N.Y., assignor to Bantam-Lite, Inc., New York, N.Y., a corporation of New York

Filed Aug. 12, 1965, Ser. No. 86,554

Term of patent 14 years

(Cl. D17—14)

FIG. 1.

FIG. 2.

FIG. 3.

FIG. 4.

FIG. 5.

FIG. 1 is a top plan view of a combined keyring and flashlight showing my new design.

FIGS. 2, 3 and 4 are front, right side and rear elevational views, respectively, thereof as seen in FIG. 1, and FIG. 5 is a left side elevational view thereof.

I claim:

The ornamental design for a combined keyring and flashlight, as shown.
